UNITED STATES PATENT OFFICE

2,655,356

CARBURETOR FOR INTERNAL-
COMBUSTION ENGINES

Herman F. Borcherts, Allison Park, Pa.

Application December 2, 1949, Serial No. 130,743

5 Claims. (Cl. 261—39)

1

This invention relates to new and useful improvements in carburetors for internal combustion engines, more particularly to low pressure variable spray fuel injectors, and it is among the objects thereof to provide a carburetor of maximum volumetric efficiency at high engine speeds and which shall maintain proper fuel and air ratio throughout part and full throttle range of engine operation.

The invention further provides in combination with a low pressure variable spray fuel injector a turbo manifold which has great advantage over the conventional Venturi type carburetor and which, by employment of a wide and streamlined manifold, necessitates the use of only a single unit where dual throat carburetors are needed.

The invention will become more apparent from a consideration of the accompanying drawing, constituting a part hereof, in which like reference characters designate like parts, and in which:

Fig. 1 is a vertical cross-sectional view of a low pressure variable spray fuel injector with turbo manifold embodying the principles of this invention;

Fig. 2 a cross sectional view thereof taken along the line 2—2 of Fig. 1; and

Fig. 3 a bottom plan view of a fuel valve embodied in the carburetor shown in Fig. 1.

With reference to the several figures of the drawing, numeral 1 designates an air horn through which air for mixing with the engine fuel is drawn as indicated by the arrows. A manually operated throttle valve 2 is disposed in a rectangular passage 3 of the air supply duct, and an air valve 4, biased by a bimetallic spring 5, Fig. 2, controls the flow of the air to a cylindrical chamber 6 that surrounds the mixing chamber 7 of the carburetor. The throttle valve 2 is provided with a lever 8 which is connected to the foot pedal of an automobile in the conventional manner, and the bimetallic spring element 5 of the air valve 4 is connected to the air valve shaft 9 as shown in Fig. 2, the spring element 5 being disposed in a cylindrical chamber 11 having inlet and outlet connections 12 and 13, respectively, for the passage of heated air as indicated by the arrows in Fig. 2.

The mixing chamber 7 is provided with vertical vanes 14 which are angularly disposed with reference to the cylindrical chamber 7, and air passing through the air duct 3 into the mixing chamber 7 is subjected to a rotating motion in passing between the vanes 14 to mix with a rich fuel mixture delivered by the mixing tube 15. The mixture passes downward in a helical path into the

5 manifold 16, as shown by the arrows in Fig. 1, and to avoid resistance of the flow of the fuel mixture, a cone 17 is provided in the center of the manifold 16. The underside of the cone 17 is heated by what may be termed a stove chamber 18 which is connected to the engine exhaust, the heated exhaust gases passing through the stove as shown by the arrows in Fig. 1. Fuel droplets not gasified in the mixing chamber 7 during the warm-up period of the engine strike the heated surface of the cone and become gasified. The base of the cone forms a circular well 19 which catches solid fuel that collects in cold weather starting, the fuel being designated by the numeral 20, Fig. 1, and will be gasified by the air moving over it and from the heat of the stove 18. Also, the fuel 20 in the well 19 acts as a primer for starting the engine as a small amount of the liquid fuel collects in the well 19 after the engine is shut off, and a small amount of fuel will also pass through the fuel valve, hereinafter described, until the final fuel pump pressure reaches zero.

20 Fuel is supplied from a pump at approximately five pounds pressure through the inlet connection 21, Fig. 1, and flows into a metering groove 22, Figs. 1 and 3, through port 23. The mixing tube 15 is an inverted funnel-shaped tube, the outer surface of which is provided with a series 25 of scooped openings 24, and the part of the air delivered through the duct 3 to the mixing chamber 7 enters the fuel mixing tube 15 through the scooped openings 24 to mix with the fuel delivered to the mixing tube. The fuel valve is designated by the numeral 25 and has a cone-shaped base 26 that seats in a complementary shaped portion of a valve base designated by the numeral 27. These conical shaped surfaces of the valve and valve base are ground and polished to a snug fit to seal off the valve while permitting free rotation of the same. Fuel is delivered from the inlet 21 through passage 23 to the metering groove 22 from which it passes through a bleeder passage 28 into a vertical passage 29 of the bleeder tube 15. The valve 25 is held in sealing engagement with the seating surface in the base 27 by a coil spring 30 disposed in a seat 31 of the valve housing, one end of the spring 30 pressing against a plunger 31 that rests on a ball bearing 32 to continually exert seating pressure of the valve 25 on its seat without interfering with the free rotation of the valve, which is automatically effected through a gear 33 and a rack 34, the latter having gear tooth engagement with a gear wheel 35 mounted to rotate with the air valve shaft 9.

3

The valve 25 is normally biased to the idle position of the engine by means of a torsion spring 36, one end of which is locked in the valve housing at 37 and the other end of which is interlocked with the shank of valve 25 at 38.

The tension of spring 36 is adjustable to regulate pressure and volume flow of air past air valve 4, and the rotation of the metering valve 25 from idle to full open flow position is also controlled by air valve 4 through the gear and rack mechanism 35 and 34. The differential in pressure on opposite sides of air valve 4 depends on the degree of opening of the throttle valve 2. The bimetallic spring 5, Fig. 2, located in the housing 11 and acting as a torsion spring on shaft 9 of air valve 4, is wound up to a maximum when cold, in which position it opposes the metering valve spring tension of spring 36 and thereby partly opens the air valve and metering valve. When the engine warms up, heat from the surface of the exhaust manifold is drawn into housing 11 through the inlet 12, passing the bimetallic spring 5, and then through outlet 13 into a passage 39 that connects with the vertical passage 29 of the metering valve 25. The warm air is useful in mixing with the fuel when it passes from the bleeder passage 28 into the vertical passage 29.

As shown in Fig. 1, any fuel leaking upward along the wall of valve 25 enters a groove 49 from which it flows through a passage 41 into the vertical fuel passage 29.

The operation of the above described low pressure variable spray fuel injector is briefly as follows.

When the engine is cranked in starting, air is drawn in through the bell horn 1 by the engine pistons, and when the throttle valve 2 is open, the air valve 4 will move in the direction shown by the arrow. This movement will rotate gear wheel 35 that in turn operates the rack 34 which interacts with the wheel 33 of the metering valve 25, thereby rotating the latter. As shown in Fig. 3, the metering groove 22 extends through an arc of 180° and tapers from zero to its maximum width at the bleeder passage 28. It also varies in depth from the shallow to the large portion whereby measured volumes of fuel are delivered from the fuel supply passage 23 to the mixing tube 15. When the metering valve 25 is rotated to the position where the maximum width and depth of groove registers with the passage 22, the maximum fuel supply is delivered to the mixing tube 15. Groove 22 is preferably V-shaped because of the expedience in cutting the groove as it runs out to zero depth and width at one end of the arc.

As previously explained, the air passing into the stationary vanes 14 in the mixing chamber 7 is given a swirling or circular motion and moves downward in the form of a helix as shown by the arrow in Fig. 1. The circulating air passing into the scoop inlets 24 of the mixing tube 15 mixes with the liquid fuel passing down the passage 29 and is further mixed with the air in the mixing chamber so that it is thoroughly mixed when it strikes the manifold 16 from which it is delivered to the valve chambers of the engine.

As the throttle valve 2 is manipulated to a greater or less open position, the fuel valve 25 is subjected to rotation through the rack 34 to supply more or less fuel to the mixing chamber, whereby the fuel supply is proportioned to the air supply and a proper fuel and air ratio is

4

maintained throughout the full range of throttle manipulation.

As previously stated, when the engine is cold the bimetallic torsion spring 5 overcomes the torsion of the fuel valve 36 to partially open the fuel valve independently of the manipulation of the throttle valve 2, so that on starting a small amount of liquid fuel passes to the mixing tube 15. After starting, the warm air from the manifold passing through the chamber 11 will enter the mixing tube through passage 29 to aid in volatilizing the liquid fuel. This heated air warms up the bimetallic spring 5 which expands to relieve the tension on the torsion spring 36 of the fuel valve, which then operates to maintain the valve 25 in a normal idling position when the throttle valve 2 is in closed position.

It is evident from the above description of the invention that the advantages of a low pressure variable spray fuel injector with the turbo manifold over the conventional Venturi type carburetor give better volumetric efficiency of fuel to the engine at high speeds, which results from the streamlined manifold, and that it will maintain proper fuel and air ratios throughout part and full throttle ranges. There are no needle valves or floats and no accelerator pump or venturi, and consequently there can be no icing up below the venturi and around the idle tube port; also only a single fuel injector unit is necessary where dual throat carburetion is used.

Although one embodiment of the invention has been herein illustrated and described, it will be evident to those skilled in the art that various modifications may be made in the details of construction without departing from the principles herein set forth.

I claim:

1. In a low pressure variable spray fuel injector, a fuel mixing chamber, an air supply passage communicating with said chamber, angularly disposed vanes in said fuel mixing chamber for subjecting the air supplied to said chamber to a swirling motion, a valve housing above said chamber, a mixing tube extending from the valve housing into said chamber, a valve disposed in said housing and having means for metering fuel to the mixing tube, said valve and valve housing having complementary conical shaped seating faces and said valve having an arcuate groove of gradually diminishing cross section communicating with a source of fuel supply, means for subjecting the valve to rotary movement for varying the fuel delivered to the mixing tube, an air valve in the air supply passage automatically responsive to the air flow in said passage, said air valve being connected to actuate said valve rotating means, whereby the ratio of the fuel supply to the mixing chamber is directly proportional to the air supply to said chamber.

2. In a low pressure variable spray fuel injector, a fuel mixing chamber, an air supply passage communicating with said chamber, angularly disposed vanes in said fuel mixing chamber for subjecting the air supplied to said chamber to a swirling motion, a valve housing above said chamber, a mixing tube extending from the valve housing into said chamber, a valve disposed in said housing and having means for metering fuel to the mixing tube, said valve and valve housing having complementary conical shaped seating faces and said valve having an arcuate groove of gradually diminishing cross section communicating with a source of fuel supply, means for subjecting the valve to rotary move-

ment for varying the fuel delivered to the mixing tube, and an air valve in the air supply passage automatically responsive to the air flow in said passage, said air valve being connected to actuate said valve rotating means, whereby the 5 ratio of the fuel supply to the mixing chamber is directly proportional to the air supply to said chamber, said valve rotating means comprising gear teeth on the valve body and a rack interacting therewith, said air valve having a gear wheel subject to rotary movement upon movement of the valve, the teeth of which interact with the teeth of said rack.

3. In a variable spray fuel injector, an annular mixing chamber, an air flow passage for said chamber terminating in a housing surrounding said chamber, said mixing chamber having angularly spaced tangentially disposed vanes for directing the air flow into the mixing chamber by a swirling motion, a fuel valve for said chamber comprising a valve housing having a valve chamber and a fuel delivering opening communicating with the mixing chamber, a conically shaped mixing tube connected to the fuel openings and extending a substantial distance into the mixing 10 chamber, said tube having scooped openings for receiving part of the swirling air passing into said mixing chamber to mix with the fuel delivered to said chamber.

4. In a variable spray fuel injector, an annular mixing chamber, an air flow passage for said chamber terminating in a housing surrounding said chamber, said mixing chamber having angularly spaced tangentially disposed vanes for directing the air flow into the mixing chamber by 15 a swirling motion, a fuel valve for said chamber comprising a valve housing having a valve chamber and a fuel delivering opening communicating with the mixing chamber, a conically shaped mixing tube connected to the fuel openings and extending a substantial distance into the mixing 20 chamber, said tube having scooped openings for receiving part of the swirling air passing into said mixing chamber to mix with the fuel delivered to said chamber.

45

communicating with said central opening, a source of fuel supply connected to the metering groove, and a source of air supply connected to the top of the valve and communicating with the central opening in said valve.

5. In a variable spray fuel injector, a mixing chamber, an air passage leading to said chamber, a fuel valve for delivering fuel to said chamber comprising a valve housing, a cylindrical valve disposed in said housing, a torsion spring normally biasing said valve in a fixed angular position, a rack and gear for subjecting the valve to rotary movement, said valve having an arcuate shaped metering groove connected with a source of fuel supply for metering the fuel delivered to the mixing chamber, an air flow responsive valve disposed in the air passage, and a throttle valve in said air passage, said air flow responsive valve being mounted on a shaft, a gear wheel on said shaft having teeth interacting with the rack for actuating the fuel valve, and a bimetallic torsion element connected to the last-named shaft and disposed in a separate air flow passage connected to a source of heated air, said last named air flow passage being connected to the fuel valve for delivery of warm air through the fuel valve to the fuel supply passage to the mixing chamber, said bimetallic torsion element overcoming the bias of the fuel valve spring to maintain the fuel valve in partially open position when the bimetallic element is at normal temperature.
